18 INVENTOR:
John C. Patterson,
BY Frally, Saul
ATTORNEYS.

UNITED STATES PATENT OFFICE.

JOHN C. PATTERSON, OF PHILADELPHIA, PENNSYLVANIA.

PAPER HOLDER OR CLIP.

Application filed May 31, 1923. Serial No. 642,446.

To all whom it may concern:

Be it known that I, JOHN C. PATTERSON, a citizen of the United States, residing at Philadelphia, county of Philadelphia, and 5 State of Pennsylvania, have invented certain new and useful Improvements in Paper Holders or Clips, of which the following is a specification, reference being had to the accompanying drawings.

10 This invention relates to temporary binders or holders adapted to clamp together sheets of material so that they can be readily gripped or released as desired, and it has more particular reference to an improved 15 holder or clip for coupon bonds and the like having a reinforced edge whereby said bonds or the like may be temporarily held or gripped.

The primary object of this invention is 20 to provide a holder or clip of simple and practical construction, which is easy to manipulate while inserting or removing an individual sheet or a plurality of such sheets therefrom.

25 Another object of my invention is to provide a holder or clip which will firmly grip and hold the bonds, papers, sheets, or other analogous articles to be retained thereby in neat superposition.

30 A further object is the provision of a holder or clip of the above referred to type that is inexpensive to manufacture, while of a serviceable, neat and attractive character.

With the foregoing and other objects in 35 view this invention comprehends improvements in the details of construction, combination and arrangement of the correlated parts, of what I now consider to be a preferred embodiment from among other possible forms devisable within the spirit of said invention and scope of the appended claims.

In the further disclosure of my said invention, reference will be had to the accompanying sheet of explanatory drawings constituting a part of this specification, and in which like characters of reference designate the same or corresponding parts in all the views.

40 Fig. I is a perspective view of my novel holder or clip in applied position, with a fragmentary portion of bond sheets, or similar articles, in clamped relation.

45 Fig. II is a detached perspective view of the upper clamping member or jaw.

Fig. III is a similar perspective view of the lower clamping member or jaw.

Fig. IV is a transverse section through the device; and

Fig. V is a similar transverse section of a 60 slightly modified form of the invention.

For convenience in describing this invention, the embodiment illustrated shows its application for clamping or gripping together a series of bonds 6, having reinforced 65 marginal edges or stubs 7, which assume the fan-like position indicated at the right hand lower part of Fig. I when temporarily retained by, and between, the jaw elements of my novel holder or clip, generally designated by the numeral 8. However, it will be obvious to those conversant with the art to which this invention appertains that my novel holder or clip 8 is capable of diversified usages, other than the specific form hereinafter described and shown; therefore it is to be expressly understood such other uses and applications are contemplated and included hereby.

The novel holder or clip 8 constituting the 80 subject matter of this application comprises a pair of opposed upper and lower jaw elements 9, 10 respectively, of suitable sheet metal having a sufficient degree of rigidity to counteract any tendency to distortion 85 when in use, as hereafter explained. As best seen by Figs. II, III and IV, these jaw elements 9, 10 are of angular substantially Z-section with one of the parallel legs extended to form a flange, and that they are 90 arranged in opposed relation; thereby providing a substantially rectangular space 11 for the bond stubs or reinforced edges 7, and opposed aligningly lateral and parallel flanges 12, 13 that constitute the gripping 95 members proper.

Referring in detail to the upper and lower jaw elements 9, 10 it will be observed from Fig. II that the former includes a longitudinal or back wall 14 having an integral 100 transverse extension or top 15 at right angles thereto, the same being appropriately creased or bent along a line parallel to said back wall 14 to provide an inwardly directed wall or jaw 16 constituting the gripping 105 edge proper. This wall or jaw 16 it will be seen is disposed in a plane substantially parallel to the back wall 14, and it is creased or bent along a line in spaced relation with respect to the top 15 to provide the herein- 110

before referred to upper flange 12 which it will be noted is parallel to the top 15 aforesaid. In like manner—but reversely arranged—the lower jaw element 10, as best seen by Fig. III comprises a longitudinal back wall 17, transverse extension or bottom 18, at right angles thereto, an upwardly directed wall or jaw 19, and the flange 13 which is disposed parallel to the bottom 18 aforesaid. However, it is to be noted that the back wall 17 is materially cut away whereby end portions 20 and a central lug 21 are provided, which serve for purposes later on explained.

15 The aforesaid jaw elements 9, 10 are disposed and retained in movable relation by means of folded-over extensions or lugs 22 at the ends of the wall 14 cooperating with the end portions 20 of the wall 17, as will be clearly understood on an examination of the drawings, and said folded-over extensions or lugs 22 constitute guides between which the aforesaid ends 20 are adapted for a limited relative movement as hereafter explained. Thus it will be readily apparent that the jaw elements 9, 10 are capable of movement towards or away from each other, while relative longitudinal displacement is prevented.

30 To provide a simple and effective means whereby the jaw elements 9, 10 may be mechanically manipulated to accomplish their opening and closing, according to the present disclosure, I employ a finger 23, of more or less springy material, conveniently pivoted at 24 to the wall 14 of the upper jaw element 9, and having a tongue or offset 25 near its free end whereby said finger 23 may be moved about its pivot 24. Intermediate its ends the finger 23 is fitted with a transverse stud 26 having the inner end thereof projected into an arcuate slot 27 in the wall 14; while on the outer end of said stud 26 there is pivoted one end of a short link 28, in turn pivoted at 29 to the hereinbefore referred to lug 21 on the lower jaw element 10 thereby establishing a latch connection between the jaw elements 9, 10. From the foregoing it will be apparent that by pressure on the finger 23 inwardly relative to the lower jaw element 10 the upper jaw element 9 will be moved upwardly in substantial parallelism away therefrom, while a reverse manipulation of said finger will effect the approachment of said jaw element 9 towards the jaw element 10; or, in other words, the movement of the jaws 9, 10 into gripping relation.

60 In order to provide means whereby the jaw elements 9, 10 may be retained in expanded- or collapsed and gripping-relation, I provide the longitudinal wall 14 of the upper element 9 with a downwardly directed tab or keeper 30, and a plurality of upwardly directed tabs or keepers 31, 32

with which the free end 33 of the finger 23 is adapted to have latching engagement, as will be readily understood on an examination of Fig. I more particularly. These tabs or keepers 30, 31, 32 are conveniently formed integral with the body of the wall 14, by being stamped or otherwise upset or embossed outwardly therefrom, as will be understood by those conversant with the sheet metal industries. When the free end 33 of the finger 23 is engaged below the tab or keeper 30 it will be clear the jaw elements 9, 10 will be expanded, or in open position, ready for the insertion of the bonds or sheets 6 and it is noteworthy that by exerting pressure on the right hand ends of said jaw elements 9, 10 as viewed in Fig. I, the outer or left hand ends—that is the ends remote from the pivot 24—will be outwardly expanded relative to said right hand ends adjacent said pivot. Thus it will be seen the jaw elements 9, 10 become slightly and divergently inclined somewhat shear fashion, whereby the device is easily slid along and over the reinforced ends 7 of the pile of bonds or sheets 6. It is further noteworthy that the arcuate slot 27 serves to limit the opening and closing of the jaw elements 9, 10 with respect to each other, while the aforesaid plurality of tabs or keepers 31, 32 make provision for the use of my novel holder or clip 8 adjustably; or, its application to different grades and quantities of bonds or sheets. Still further it will be seen that the channel shaped part cross-section of the jaw elements 9, 10, afforded by the portions 14, 15, 16, and 17, 18, 19, respectively, ensures an adequate clearance 11 for the free insertion of the reinforced edges 7; while, when said jaw elements are locked in gripping relation, said reinforced edges 7 can readily expand fan fashion, whereby any tendency to buckling or distortion is prevented. Again, when the device is in use, it will be observed that the flanges 12, 13 are disposed in parallel gripping engagement on the bonds or sheets 6 whereby the latter are temporarily bound and evenly held without fear of any lateral displacement.

65 In some instances, or where the sheets of material temporarily bound by my novel holder or clip are of a tough and durable character, I may dispense with the flanges 12, 13 and utilize the opposed aligning edges 34, of the walls or jaws 16, 19 for gripping purposes, as will be readily understood from Fig. V without further explanation or description.

When it is desired to separate or open the jaws 9, 10, the operator releases the free end 33 of the finger 23 from latching engagement with the tab or keeper 32 by exerting an upward pull on the tongue or offset 25, while the inherent springiness of said finger permits its lateral displacement so

- that it can be moved over the tabs or keepers 32, 31 in a downward direction. Immediately the said finger 23 is released as just set forth, the previously pinched or compressed bonds or sheets 6 will automatically expand slightly thereby freeing the upper jaw element 9, whereupon said jaw element can be elevated or moved relatively away from contact with the bond or sheet stubs 7. 10 by depression of the finger 23 until the free end 33 thereof is snapped beneath the tab or keeper 30, longitudinal displacement and smooth guidance being effectively ensured by the cooperation of the parts 20, 22. 15 When the jaw elements 9, 10 are thus separated it is noteworthy they will be located in substantial parallelism whereby any one or all of the stubs 7 can be smoothly removed without impedance from any inclined part or parts.

In addition to the advantages above enumerated, it will be obvious that my novel holder or clip 8 comprises but two main parts 9, 10 which can be constructed of appropriate sheet metal by a simple stamping operation; and while I have illustrated and described certain specific instrumentalities, it, of course, will be apparent that various detail changes may be effected without materially departing from the spirit of this invention, the scope whereof is expressed by the subjoined claims.

Having thus described my invention, I claim:

- 35 1. A holder or clip comprising a stationary jaw of substantially Z-section with one of the parallel legs extended to form a flange, a corresponding movable jaw, means preventing longitudinal displacement of said jaws, and an operating member adapted to latchingly retain the jaws in varied parallelism.

2. A holder or clip comprising opposed substantially Z-section jaws one of which is movable relative to the other, each of said jaws having one of its legs extended to afford an angled flange, means preventing longitudinal displacement of said jaws, and an operating member to latchingly retain the jaws in varied parallelism.

3. A holder or clip comprising a stationary jaw of substantially Z-section material having one of its parallel legs extended to afford a right-angled flange, a movable jaw of corresponding cross-section, means preventing longitudinal displacement of the jaws, and a latch member adapted to retain the jaws in varied parallelism.

4. A holder or clip comprising complementary Z-section jaws of sheet material, one of which is movable relatively to the other, guides integral with one of said jaws to prevent longitudinal displacement, and an operating member adapted to latch the jaws in varied parallelism.

5. A holder or clip comprising complementary members of substantially Z-section sheet material with one pair of parallel legs angularly fashioned to form co-operative flanges and the other pair functioning as gripping jaws, means preventing end-wise displacement of said members, a flexible latch and cooperative means adapted to hold the jaws in varied parallelism.

6. A holder or clip comprising a stationary and a movable member of substantially Z-section material disposed in lapping relation, one pair of parallel legs of said members providing longitudinally aligned gripping jaws, means preventing longitudinal displacement of said jaws, and a flexible operating finger adapted to latch said jaws in varied parallelism.

7. A holder or clip comprising substantially Z-section members with one pair of the parallel legs right-angled to afford co-extensive flanges disposed in lapping relation, means slidably connecting said angled legs, the other pair of parallel legs constituting longitudinal inset gripping jaws having lateral flanges, and a flexible operating finger adapted to latch said jaws in varied parallelism.

8. A holder or clip comprising substantially Z-section members, fold-over lugs at the ends of a longitudinally flanged leg of one member engaging the abutting similarly flanged leg of the other member, the other parallel legs constituting longitudinally inset gripping jaws, a flexible operating finger pivoted on the flanged leg of one member adapted for latching connection with the flange on the other member to hold said members in clamped relation, and means whereby said finger retains the jaws in varied parallelism.

9. A holder or clip comprising substantially Z-section members arranged in lapping relation, means slidably connecting the one member to the other, longitudinal inset gripping jaws having lateral flanges afforded by parallel legs of said members, a flexible latch connection between said members, means limiting the opening and closing of the gripping jaws, and means whereby the latch connection retains the jaws in varied parallelism.

10. A holder or clip comprising opposed substantially Z-section members having parallel legs angled to provide abutting flanges, means slidably connecting the flange of one member to the complementary flange of the other, longitudinal inset gripping jaws afforded by the other parallel legs, a latching connection including an extended finger between the abutting flanges, a pin and slot limiting relative movement of the gripping jaws, and means whereby the finger retains said jaws in varied parallelism.

11. A holder or clip comprising opposed

substantially Z-section members having parallel legs angled to provide abutting flanges, means slidably connecting the abutting flange of one member to the complementary flange of the other, longitudinal inset gripping jaws afforded by the other parallel legs, a latching connection including a flexible finger between the abutting flanges, a pin and slot limiting the movement of the jaws, and a series of offsets on one flange for en-

gagement by the free end of the aforesaid finger to arrest the gripping jaws in varied parallelism.

In testimony whereof, I have hereunto signed my name at Philadelphia, Pennsylvania, this 28th day of May, 1923.

JOHN C. PATTERSON.
